UNITED STATES PATENT OFFICE.

EVA KELLER, OF PASADENA, CALIFORNIA.

VOICE PLACER.

Application filed April 27, 1927. Serial No. 186,917.

My invention is a voice placer to aid a person in learning to sing or in singing to have the proper placing and control of the voice.

An object of my invention is to enable a singer to listen to their own voice and to detect if it has the proper placement, the tone quality, etc.

A more specific object of my invention is a device which a person learning to sing or an 10 accomplished singer may hold at the proper distance from the mouth, such device receiving the sound waves and deflecting these back so they may be readily detected by the ear to enable the singer to ascertain the correct 15 placement of the voice and the tone by the sound as received through the ear.

The present invention may be considered as an improvement over my patent for a voice placer No. 1,621,207, issued March 15, 1927. 20 In the present invention I do not have any part of the device touch the upper teeth but the device is held at a desired distance away from the mouth so that the full tone of the singing voice will be collected by reflecting 25 surfaces and resonance chambers.

In constructing my invention I have a main large reflector which is held in fixed relation to the handle. This is preferably somewhat spherical. In front of this I have another reflector which has the lower part semi-cylindrical and the upper part has a spherical 30 curve. This forms a species of resonance chamber. Pivotal secured to the resonance chamber is a hood which has a somewhat spherical curvature and forms a combination of an adjustable reflector and adjustable resonance chamber.

On the main resonance chamber I have a 40 pair of jaw type devices, the lower one of which is preferably stationary and the other one pivoted, so that these may open or close to a greater or lesser extent to control the relative volume of sound passing through the jaws to the main resonance chamber. Above 45 the upper jaw is a deflector which may be formed with apertures therethrough, this deflector being pivoted on the front of the main resonance chamber, and connected to said deflector are vibrating fingers formed of resilient readily vibratable material.

My invention will be more readily understood from the following description and drawings, in which:

Figure 1 is a perspective view of my inven-

tion showing the manner in which the same 55 may be used.

Figure 2 is a side elevation of the invention.

Figure 3 is a front elevation taken in the direction of the arrow 3 of Fig. 2. 60

Figure 4 is a longitudinal section on the line 4—4 of Fig. 3 in the direction of the arrows.

Figure 5 is a section on the line 5—5 of Fig. 4 in the direction of the arrows. 65

Figure 6 is a section on the line 6—6 of Fig. 4 in the direction of the arrows.

In manufacturing and assembling my voice placer I have a main reflector 11 which is preferably spherically curved, and to the 70 lower end of this I attach a handle 12. This handle preferably has a forward curve 13 to allow gripping with the first and second fingers behind the curve, thumb in front, and tip end 14 to place the little finger in front of, 75 and thus to hold the device in a steady position.

A main resonance chamber 15 is formed by a structure 16 which at the lower part 17 is semi-cylindrical, and has an upper portion 18 with a spherical curve. This structure is rigidly connected to the main reflector 11 and when the back of such structure is vertical, the main reflector tilts slightly backwardly 80 therefrom.

A second reflector and resonance device 19 is connected by a pivot joint 20 to the lateral sides of the resonance chamber structure, and this reflector preferably has a spherical curvature, as indicated by the 85 numeral 21. The line 22 indicates a diametrical line of the sphere, the back portion 23 being cut away so that such second reflector may be accommodated to the curve of the resonance chamber structure 16. 90

A lower jaw 24 is rigidly connected to the side of the main resonance structure 16, this jaw preferably having a front rim 25, side rims 26, and a back rim 27, thus forming a hollow recess 28. The upper jaw 29 is pivotally mounted on a bracket 30. This jaw likewise has a recess 31 formed by the front rim 32, the back rim 33, and the side rims 34, this construction allowing the upper jaw to 100 be tilted so as to increase or decrease the opening between the front rims of the upper and lower jaws and the space between the back rims of such jaws.

105

A deflector plate 35 is pivotally connected to the sides by pivot pins 36 of the resonance chamber structure 16, this having a slight curvature, as illustrated in Fig. 3, and is also 5 preferably provided with a series of apertures 37 therethrough. Rigidly connected to the deflector plate 35 and spaced slightly rearwardly therefrom are a series of vibrating fingers or teeth 38 having a supporting base 39 10 directly behind the deflector plate 35. There are also depending vibrating fingers 40 connected to the plate or strip 39. These hang downwardly from the lower end of the deflecting plate 35 and when such plate is oscillated 15 or tilted in different positions the vibrating fingers move with the plate.

The manner of using and functioning of my voice placer is substantially as follows:

The device is held away from the mouth 20 while the singer is producing the various tones in singing or in singing a song, this being held preferably so that the main volume of the sound strikes between the fixed jaw 24 and the tilting upper jaw 29. As above 25 mentioned, the upper jaw may be tilted so as to open or close the structure to a greater extent and allow a greater or a lesser volume of the tone to impinge in the resonance chamber structure 16. This structure acts in effect 30 as a resonance chamber and also as a reflector, part of the sound waves being deflected by the semi-cylindrical part backwardly towards the singer and part of the sound waves being deflected through the partly spherical structure 18, impinging on the pivoted reflector 35 19. Part of the sound waves pass behind this pivoted reflector, striking the main reflector 11, and also part of the sound waves direct from the mouth strike this reflector 40 which is intended to be held in such a position that the sound will be reflected back to the singer's ears.

All of the sound waves directly from the mouth do not strike in the jaws but some of 45 them strike the deflector plate 35. As this plate is perforated, the sound waves impinge against the vibrating fingers 38 at the back of the plate and also some of the sound waves are deflected by the plate against the vibrating fingers 40 and these set up a resonant vibration.

As above mentioned, the upper jaw 29, the deflecting plate 35, and the second reflector 19, are adjustable on the main resonance 55 chamber structure 16 so that the singer can tilt these until the desired effect is obtained. That is by tilting these and holding the whole device in various positions, the singer may place the structure in such a position as to have the sound of their voice reflected back 60 in the desired manner.

Another advantage of my voice placer is that a singer may sing very softly, without any forcing of the voice, and still have the 65 sound reflected back in such a manner that

they obtain a proper interpretation as to the production of the tones and by opening the jaws to a greater or a lesser extent and tilting the deflecting plate 35, as well as by adjusting the second reflector 19, slight differences of 70 effect may be obtained.

In the claims where the second reflector 19 is designated as a hood, it is intended that this form a covering over the resonance chamber structure 16, and so shaped as to have a 75 resonance effect to act as a reflector and also to reflect sound waves to the main reflector 11. Where vibrating fingers are specified, it is to be understood that other vibrating devices may be utilized and be associated with a reflecting plate similar to the element 35; and also in referring to adjustable jaws it is not necessary that only the upper jaw be 80 adjustable.

I find a suitable way to secure the handle 85 12 to the main reflector 11 is by bending the upper end of the handle and securing these parts together by a rivet 41 and the bottom of the main resonance chamber structure 16 has an extension 42 which is secured to the handle by a rivet 43 or the like. This extension has a series of perforations 44 which allow a certain amount of sound to pass through and between the bottom of the structure 16 and the lower portion of the main 90 reflector 11.

Each of the jaws is provided with a groove 45 adjacent the front rim and this increases the relative depth of these, causing them to function in a certain manner as resonance 100 devices.

Various changes may be made in the principles of my invention without departing from the spirit thereof, as set forth in the description, drawings and claims. 105

I claim:

1. A voice placer comprising in combination a main reflector having a substantially spherical reflecting surface, a structure having a resonance chamber positioned in front of the main reflector, such structure having a wall semi-cylindrical in shape, the upper portion being spherical shaped, and means to hold the main reflector and the resonance chamber structure to receive sound waves produced by 110 a singer and to reflect these to the singer's ears. 115

2. A voice placer comprising in combination a main reflector, a resonance chamber structure rigidly secured in front of the reflector, and a hood having a curved internal structure connected to the resonance chamber structure. 120

3. A voice placer comprising in combination a main reflector, having an internal 125 somewhat spherical surface, a resonance chamber structure secured in front thereof, said structure having a transversely curved surface, and an upper partly spherical surface, and a hood connected to the resonance 130

chamber structure above same, the hood being curved somewhat spherically.

4. A voice placer comprising in combination a main reflector somewhat spherical in contour, a resonance chamber structure secured in front thereof, having a lower portion semi-cylindrical in transverse section and with the upper portion partly spherical, a dome shaped hood pivotally connected to the resonance chamber structure fitting over the top thereof, and means to receive and deflect sound waves positioned in front of the resonance chamber structure.

5. A voice placer, as claimed in claim 4, and means to receive and deflect sound comprising jaws having an opening at the front and the back.

6. A voice placer, as claimed in claim 4, means to deflect the sound waves comprising adjustable jaws having an opening at the front and the back, and a deflecting plate.

7. In a voice placer a resonance chamber structure having a curved body portion, a pair of jaws connected to the open front thereof, means to support the resonance chamber structure with the open part towards the singer's mouth, the jaws having an opening towards the singer's mouth and towards the resonance chamber.

8. In a voice placer, as claimed in claim 7, a deflector plate adjustably secured to the resonance chamber structure and positioned adjacent the jaws.

9. In a voice placer, as claimed in claim 7, a deflector plate adjustably secured to the resonance chamber structure and positioned adjacent the jaws, and vibrating fingers held in a fixed relation to the deflector plate.

10. A voice placer comprising in combination a main reflector somewhat spherical in contour, a resonance chamber structure secured in front thereof, said structure being curved in cross section and having a curve in the upper portion, a dome shaped hood pivotally connected to the resonance chamber structure, and a pair of jaws mounted on the open side of the resonance chamber structure.

11. A voice placer, as claimed in claim 10, the jaws being adjustable, and having

a recess with rims at the front and the back, 50 there being a passage between the front rims and the back rims for sound waves.

12. A voice placer, as claimed in claim 10, and a deflector plate adjustably mounted on the open side of the resonance chamber 55 structure, said plate having vibrating fingers held in fixed relation thereto.

13. A voice placer comprising in combination a main reflector of partly spherical contour, a resonance chamber structure secured 60 in front thereof, said structure being curved in transverse section, having a curved upper end and open at the front, a dome shaped hood pivotally connected to the resonance chamber structure and adjustable over the 65 upper end thereof, a pair of jaws secured to the front of the resonance chamber structure, at least one of such jaws being adjustable to increase or decrease the distance between the open mouth of the jaws and the 70 back of the paws, and an adjustable reflector plate positioned above the jaws, said plate having vibrating fingers secured to the back thereof and depending below the rear edge of such plate. 75

14. A voice placer comprising in combination a structure forming a main reflector, a second structure fixedly connected thereto and mounted in front of the main reflector, said structure being positioned with one edge 80 adjacent the main reflector and forming a resonance chamber, the front edge of the structure having a resonance chamber and the structure having the main reflector being in planes at an angle to each other. 85

15. A voice placer comprising in combination a structure having a main curved reflector, a second structure rigidly connected to the first structure having a resonance chamber mounted therein, said resonance 90 chamber having a cylindrically curved wall, the lower end of the second structure being secured adjacent the lower edge of the first structure, whereby the resonance chamber is partly housed in the main reflector. 95

In testimony whereof I have signed my name to this specification.

EVA KELLER.
